CHARLES F. KLEPPER, OF COVINGTON, KENTUCKY.

DESIGN FOR AN AQUARIUM AND STAND FOR SAME.

Design No. 12,772, dated February 21, 1892.

CHARLES F. KLEPPER.

UNITED STATES PATENT OFFICE.

CHARLES F. KLEPPER, OF COVINGTON, KENTUCKY.

DESIGN FOR AN AQUARIUM AND STAND FOR SAME.

SPECIFICATION forming part of Design No. 12,772, dated February 21, 1882.

Application filed January 14, 1882. Term of patent 7 years.

To all whom it may concern:

Be it known that I, CHARLES F. KLEPPER, a citizen of the United States, residing at Covington, in the county of Kenton, and the State of Kentucky, have invented and produced a new and original Design for Aquaria and Stands for Same, of which the following is a specification, reference being had to the photograph forming part thereof.

10 My invention relates to aquaria which are to be employed for ornamentation within doors; and it consists in general in a peculiar configuration of the stand and the body of the aquarium.

15 Figure 1 is a perspective view of the aquarium and stand entire, and Fig. 2 represents one of the legs of the stand.

There are preferably four legs to the stand, each one of the legs being of the form shown in Fig. 2. The upper part of each leg is composed of a double column, A, the interspace being occupied by filigree-work. Near the center of each leg is a straight bar or rail, a, and below this the leg is composed of a double scroll, B. Springing from the outer edge of each leg is a bracket, C, composed of a straight bar and scroll-work, and at the end of the bracket is a stand, b, for supporting a flower-pot or other ornament. These legs are secured to the under side of slab or top D. Cross-braces d are attached to the rails a of each leg, each brace extending from one leg to the one at the opposite corner of the top D, the braces thus crossing each other at their centers. These braces d are bent down, as shown in Fig. 1, and at their point of crossing is placed a stand, d', for supporting an ornament. Around the edge of the top D is a scalloped border, e, and upon this top rests the aquarium E, the base 35 E' of which is beveled, as shown, and ornamented by suitable engraving. At each corner of the base is a round column, G, the tops of said columns being surmounted by a suitable ornament. The upper rails, c', of the aquarium unite the top ends of the columns.

40 While I prefer to employ four legs of the stand, it will be obvious that three or more legs may be employed without materially altering the design of the stand, the principal 45 feature of which design consists in the par-

ticular configuration of each leg, as herein described.

Another feature of the design of the stand consists in the various brackets for supporting ornaments.

The principal features of the design of the aquarium are the beveled base and the column surmounted by appropriate ornaments.

Obviously any one or more of the portions of my design (excepting the aquarium proper—that is, the fish and flower receptacle) may be advantageously employed, supporting and forming a part of ornamental tables, jardinières, and the like, and all such applications will come within the scope of my invention.

The design for the aquarium proper may be applied to aquaria supported in ways and by means other than I have shown, and will then still come within the scope of my invention.

Having thus described my design, what I claim as new, and desire to secure by Letters Patent, is as follows:

1. The herein-described design for an aquarium and other stands, consisting of three or more legs, each leg consisting of an upper part composed of a double column, the interspace being occupied by filigree-work and a lower portion composed of a double scroll, the upper and lower portions of the legs being separated by a horizontal rail, the legs being surmounted by an appropriate top or slab, substantially as described.

2. The design for aquarium and other stands, consisting of three or more legs, substantially as herein described, surmounted by a top or slab, D, the several legs being united by the cross-braces d, and each leg provided with a bracket for supporting an ornament, substantially as described.

3. The design for an aquarium and other stands, consisting of three or more legs formed after the pattern herein described, the legs being surmounted by a top or slab, D, having a scalloped border, e, and the lower part of the legs being connected by the cross-braces d, formed as shown, and having a stand, d', for supporting an ornament, substantially as described.

4. The design for aquaria and stands for

same and other stands, the stand being formed after the pattern substantially as herein described, and the aquarium having a beveled base and the round columns G, each column being surmounted by an appropriate ornament, substantially as described.

5. The herein-described design for aquaria, consisting of a beveled base, E', suitably en-

graved, and the round columns G, the tops of which are surmounted by appropriate ornaments and connected by the top rails, c', substantially as described.

CHARLES F. KLEPPER.
